OUTLET BOX ATTACHMENT MEANS

Original Filed April 4, 1924

UNITED STATES PATENT OFFICE

GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY

OUTLET BOX ATTACHMENT MEANS

Original application filed April 4, 1924, Serial No. 704,101. Patent No. 1,683,742, dated September 11, 1928.
Divided and this application filed February 7, 1925. Serial No. 7,450. Renewed April 10, 1931.

My invention relates to outlet box construction, and more particularly relates to adjustable means for supporting the box on a wall or partition, and means for supporting electrical switches, or other devices, in the box.

This application is a division of my prior application, Serial No. 704,101, filed April 4, 1924, for outlet box construction, Patent 10 1,683,742 of September 11, 1928, and as aforesaid relates particularly to box attachment and switch supporting devices.

Heretofore in outlet box construction it has been customary to cut the blank from 15 which the box body is formed in such a way that there is a lug or tab integral with and extending from the top of each side of the box. These lugs are then tapped and bent over and the cover plate or switch, or another unit, is held in place in the box by 20 being secured to these lugs. This method of forming these lugs on the box necessitates using for the blank a sheet of metal sufficiently large to allow the lugs to be 25 formed thereon and requires the cutting away and discarding of a substantial quantity of metal. If these lugs are not formed on the blank, the size of the sheet from which the blank is cut may be smaller. The saving 30 which can be effected by so reducing the size of the sheet from which the blank is cut so as not to include the switch supporting lugs, and by not cutting away and wasting the metal between the lugs, may seem trifling, but in the art of outlet box construction this saving assumes major proportions, 35 due to the necessity of reducing the cost of these articles to the minimum to meet the requirements of contractors and dealers, and to meet competition. A saving of even a 40 small fraction of a cent per box will be considered with great seriousness by manufacturers, contractors and dealers, and may be the determining factor as to whether or 45 not the box will be successful commercially. Saving and reduction of cost in other parts of the construction are, of course, equally important, so long as efficiency and practicability are not sacrificed.

Accordingly, the principal object of the

part of my invention covered in this application is to provide practical and efficient box attachment and switch supporting means which tend to reduce the manufacturing cost of the box. Another object of my invention is to provide box attachment and switch supporting devices which may be assembled on the box or removed therefrom readily, easily and quickly, and, if desired, may be retained on an unmounted box permanently ready for use, thus preventing these elements from becoming mislaid and lost, and eliminating the necessity of handling them as separate detached pieces when the box is to be installed or, if a gang box, when it is extended or reduced in size. A further object of my invention is to make the various parts small and simple and so shaped as to conserve material.

Other objects of my invention will be in 70 part obvious and in part pointed out hereinafter.

In accordance with my invention, I provide a construction wherein a single screw serves to detachably retain a separate switch supporting element and a separate box supporting element on a box wall, these elements being attachable to and removable from the wall without requiring the screw to be removed from these elements, and permitting removal, adjustment and reversal of the box supporting element without removing the screw from the wall, thus facilitating assembly and adjustment of the parts, reducing the number which must be handled separately, and conserving time and labor. The switch and box supporting elements are on opposite sides of the box wall, which is notched for the screw, and the screw penetrates one element and is threaded into the other in such a way that the two elements may be clamped firmly in position against the box wall. Preferably, the box supporting element is notched for the screw to permit reversal without requiring the screw or the switch supporting element to be removed from the box wall.

In order that a clearer understanding of my invention may be had, attention is hereby directed to the accompanying drawings, 100

forming a part of this application and showing one possible embodiment of my invention.

Referring to the drawings:

Fig. 1 is a top view of an outlet box construction, including switch and box supporting devices, embodying my invention; Fig. 2 is a side view of the same; Fig. 3 is a sectional view, and is taken on the line 3—3 of Fig. 2; Fig. 4 is a sectional view of a portion of the construction, and is taken on the line 4—4 of Fig. 2; Fig. 5 is a side view of the same portion of the construction showing the box supporting element mounted in a different position of adjustment; and Fig. 6 is a view similar to Fig. 5, but shows the box supporting element in a third position of adjustment. Similar reference characters refer to similar parts throughout the several views of the drawings.

Referring to the drawings, the outlet box comprises a bottom 1, side walls 2 and 3, and end walls 4 and 5. For association with the box I provide attachment elements 6 whereby the outlet box may be secured in place in a wall or other structure, and supporting elements 7 whereby cover plates, switches or other units may be detachably supported in or on the box. Elements 6 have a flange 8 adapted to seat against the side of box wall 2 or 3 between two guide bosses 9 formed on the wall, and have a box attachment flange 10. Elements 7 have a flange 11 seating against the inside of the box wall 2 or 3, and have an attachment flange 12 provided with a threaded screw hole 13. At the lower end of flange 11 is a circular boss 14 provided with a threaded hole 15 for a screw 16. Each side wall 2 and 3 has an aperture 17 and a slot 18 narrower than the aperture 17 extending therefrom to the top edge of the wall. The boss 14 of the switch supporting element is wider than the slot 18, but is small enough to seat in the aperture 17. The head of the screw 16 is wider than the aperture 17, but its shank may pass through the slot 18. Accordingly, when the screw is tightened, the boss 14 is drawn into the aperture to prevent removal of the switch supporting element from the body section wall, and when the screw is loosened the switch supporting element may be mounted on or removed from the wall without removing the screw from the element.

The flange 8 of each box supporting element 6 has a notch 19 open adjacent the attachment flange 10, and adapted to receive the shank of the screw 16. By adjusting the notch 19 with respect to the screw 16 and then tightening this screw, the box supporting element may be secured to the body section wall in various positions. (See Figs. 5 and 6.) Alongside of the notch 19, the flange 8 has a key hole slot comprising

an aperture 20, larger than the head of the screw 16, and a communicating slot 21 narrower than the head of the screw, the key hole slot being so disposed that the box supporting element 6 may be secured to the box in inverted position (as shown in Figs. 2 and 3) by engaging the key hole slot of the flange 8 with the screw 16. By the slot and aperture arrangement in applicant's supporting bracket the outlet box is adapted to be removably positioned and secured to walls of various characters. When the outlet box is to be positioned on walls to be plastered, for instance, the bracket is hung in the position shown in Figs. 2 and 3, the flange portion 10 being secured to the lath, and the plaster disposed between flange 10 of the bracket and flange 12 of the switch supporting element. Again it may be desirable in non-plastered walls to have the securing flange 10 of the box supporting element positioned flush with the outside of the box as shown in Fig. 5. If a thin wall covering material, such as beaver board, is used, the bracket may be adjusted to suit the various thicknesses of covering material inserted between flanges 10 and 12, as shown in Fig. 6. Two slots are used to provide for adjustability of the bracket to accommodate all thicknesses of wall covering. It is evident that if only one slot were used no adjustability would be provided for between the minimum upright position and the maximum inverted position of the flange 10. Furthermore, if only one slot were used positioned in the middle of the bracket 8, the projecting head of screw 16 would interfere with the insertion of the screw through hole 13, of bracket 7. Therefore, two slots are necessary. It is further evident, by referring to Fig. 2, that the box-supporting bracket 6 cannot be removed by forcing the bracket upwardly, since the overhanging flange 12 abutting against plate 8 prevents upward movement of the support. Therefore, applicant has provided the enlarged aperture 20 to permit removal of the bracket by downward movement thereof. It will be apparent that the element 6 may readily and easily be adjusted and reversed on a box wall without requiring the screw 16 to be removed from the element 7 or from the wall.

It will be readily apparent that the disclosed construction has all the advantageous features and characteristics mentioned heretofore, and that all the objects of my invention are attained thereby.

As many changes could be made in the above construction, and as many different embodiments of this invention could be made without departing from the scope thereof, it is intended that all matter contained in the above description or shown in

the accompanying drawings be interpreted as illustrative and not in a limiting sense.

What I claim is:—

1. In outlet box construction, in combination, a box including a wall having an aperture and a slot narrower than said aperture and extending therefrom to an edge of said wall, a switch supporting element having a boss wider than said slot and engageable in 10 said aperture, and a screw passing through said wall and engaging said boss, the head of said screw being wider than said aperture and the shank of said screw being narrower than said slot, whereby when said screw is 15 tightened said boss is drawn into said aperture to prevent removal of said element from said box wall, and when said screw is loosened said element may be removed from and may be mounted on said box wall without 20 removing said screw from said boss.

2. In outlet box construction, in combination, a box having a wall, a box supporting element having a flange seatable against said box wall, and a headed screw detachably and 25 adjustably retained on said wall for detachably securing said element to said wall for adjustment and reversal with respect thereto, the said flange having a notch open at one end and narrower than the head and 30 wider than the shank of the screw, and having also a key-hole slot comprising an aperture larger than the head of the screw and a communicating slot narrower than the head of the screw, whereby the flange may 35 be placed in engagement with the screw alternatively at the notch and at the key-hole slot.

3. In outlet box construction, in combination, a box having a wall, a box supporting 40 element having a flange seatable against said box wall, and a headed screw detachably and adjustably retained on said wall for detachably securing said element to said wall for adjustment and reversal with respect 45 thereto, the said flange having a notch open at one end and narrower than the head and wider than the shank of the screw, and having also a key-hole slot comprising an aperture larger than the head of the screw and a 50 communicating slot narrower than the head of the screw, whereby the flange may be placed in engagement with the screw alternatively at the notch and at the key-hole slot, 55 there being on said wall two guide bosses for said flange.

4. In outlet box construction, the combination with a box wall having an aperture therein, a switch supporting element having 60 a flange disposed against the inside of said box wall, a box supporting element having a flange seatable against the outside of said box wall, said flange having a slot and a screw having a head wider than the slot extending through said flange and said box 65

wall and engaging said switch supporting element to retain said box supporting element and said switch supporting element on said box wall.

5. In outlet box construction, the combination with a box wall having an aperture therein, a switch supporting element having a boss portion adapted to seat in said aperture from inside the box wall, a box supporting element having a flange seatable 70 against the outside of said box wall, said flange having a slot cut therein, and a screw extending through said flange and said box wall and operatively engaging said switch supporting element to retain said box supporting element and said switch supporting element in position on said box wall, said screw having a head wider than said slot.

This specification signed this 3rd day of February, 1925.
